UNITED STATES PATENT OFFICE.

JOSEPH F. JAWOROWSKI, OF CLEVELAND, OHIO, ASSIGNOR OF ONE-HALF TO SAMUEL E. DETTELBACH, OF CLEVELAND, OHIO.

HYDRAULIC REDUCTION DRIVE.

Application filed February 20, 1925. Serial No. 10,676.

To all whom it may concern:

Be it known that I, JOSEPH F. JAWOROWSKI, a citizen of the United States, residing at Cleveland, in the county of Cuyahoga, State of Ohio, have invented certain new and useful Improvements in a Hydraulic Reduction Drive, of which the following is a specification.

My invention pertains to an improvement in a hydraulic reduction drive, my general object being to provide a rotary device in which liquid may be continuously circulated and utilized to transmit power at a reduced speed, substantially as hereinafter shown and described and more particularly pointed out in the claims.

In the drawings accompanying this application, Fig. 1 is a sectional view transversely through the device on line 1—1 of Fig. 4. Fig. 2 is a horizontal section of the rotor member on line 2—2 of Fig. 1. Fig. 3 is a horizontal section on line 3—3 of Fig. 1. Fig. 4 is a longitudinal section on line 4—4 of Fig. 1.

The invention comprises a circular casing 2 having an integral base 3 adapted to support the device in a stationary position. Casing 2 is closed at its ends by removable plates or walls 4—4' having hubs extending therefrom within which two separate shafts 5 and 6 are journaled. A packing nut 7 and gland 8 may be used at each hub to prevent leakage of the liquid confined within casing 2. A filling opening 9 is shown at the top of the casing which is adapted to be closed by a screw plug 10. Shaft 5 is an integral or fixed part of a plate or disk 11 which is secured to a heavy ring or annular body 12 contained within casing 2. A similar plate or disk 14 is affixed to the opposite side of body 12 and has a short extension 15 sleeved upon shaft 6 and extending into a counterbore 17 in the hub of plate 4'. Annular body 12 is thus supported to rotate freely within the casing independently of shaft 6. This shaft is formed with a pair of eccentric or crank portions 18 and 19 adapted to project into separate circular chambers 20—20 formed within the end faces of body 12. These chambers are concentric with the axis of annular body 12 and a wall 22 separates the chambers. A central opening 23 in wall 22 permits annular body 12 to be sleeved over the eccentric portions of shaft 6, and a short exten-

sion 24 of shaft 6 projects into a counterbore 25 formed centrally within plate 11 and shaft 5, thereby providing a bearing at the inner end of shaft 6. Each eccentric or cam portion on shaft 6 carries a separate roller 26, and each roller has rolling engagement with the circular wall of the circular chamber within which it is confined. The two cranks and rollers are offset on the shaft in respect to each other, preferably one hundred and eighty degrees.

Each flat end face of body 12 is also formed with an oblong chamber 27 having two short passages 28 at one end which communicate with the circular chambers 20 directly opposite thereto. Two oscillatory members 29—29 are confined within chamber 27, the free moving end of each being in the form of a curved blade 30 which acts as an oscillatory abutment. The curved face 75 of blade 30 engages the curved side 31 of passage 28 and the rabbeted end 32 of the blade projects beyond the passage into contact with the peripheral surface of roller 26. A narrow slot or a round opening 33 of 80 small diameter extends from the circumference of annular body 12 to chamber 27, thereby permitting a predetermined amount of liquid to flow under restriction out of chamber 27 into the annular space 34 with- 85 in casing 2. The liquid passes into chamber 27 from the crescent-shaped space formed by roller 26 and the round wall of circular chamber 20. Abutment member 30 divides this crescent shaped space into 90 two parts *a* and *b*, respectively, and a concentric intake channel 35 is provided within body 12 which channel extends from a reduced central part of the body to a straight passage 36 leading to the convex side of 95 abutment member 30 where it may have open communication at corner 37 with the space marked *b*. The rabbeted end 32 of member 30 permits communication between space *b* and intake passage 36 when said member is 100 retired entirely within outlet passage 28 by roller 26. It follows that with the rollers offset one-hundred and eighty degrees that the respective abutment members will 105 occupy different oscillatory positions and act to promote a uniform flow of liquid passing through revolving body 12. A uniform pressure is also established within casing 2 and a differential rotation effected between the two shafts when power is applied to one 110

of the shafts, it being understood that the small opening 33 restricts the outflow of liquid while the larger channels 35 permit free inflow. The outer end of channel 35 5 may also flare to larger dimensions to promote free circulation of the liquid during rotary movements, and its offset relation to the reduced central part of body 12 also promotes inflow. The curved channels 35 10 are in reality supply pockets for the intake side of the segmental spaces b.

A rocking element 38 is pivoted at its middle upon a pin 39 extending into chamber 27, and the outer ends of this element 15 bear down upon upright pins 40 which are seated in sockets within the free moving ends of oscillatory member 29, thereby holding these members constantly in engagement with the rollers.

20 What I claim is:

1. A fluid power-transmitting device, comprising a casing, a rotatable body therein having a shaft journaled within said casing and formed with circular chambers, a crank 25 shaft having rollers operating in said chambers, oscillatory abutments mounted upon said body and engaging said rollers, and said body having passages therein on opposite sides of said abutments adapted to permit circulation of a fluid through said chambers and casing.

2. A power-transmitting device, comprising a casing containing a liquid, a chambered body rotatably mounted within said 35 casing, a shaft having eccentrics and rollers adapted to revolve within said chambered body, oscillatory abutments engaging said rollers, and said body having openings of restricted area and passages of larger area 40 between its exterior and interior on opposite sides of said abutments.

3. A power transmitting device, comprising a casing containing a liquid, a round body having a shaft journaled within said

casing, said body having circular chambers 45 in its sides, a shaft extending through said casing having offset eccentric portions projecting into said chambers, rollers upon said eccentric portions adapted to engage the circular walls of said chambers with a rolling 50 movement, oscillatory members mounted upon said body having abutment portions engaging said rollers, and said body being spaced apart from the walls of said casing and having openings of restricted area in its 55 circumference in open communication with said chambers at one side of said abutments and formed with passages leading from said chambers on the opposite side of said abutments to the space within the casing surrounding said body.

4. A power transmitting device, comprising a casing containing a liquid, a rotatable body within said casing having circular 65 chambers, an eccentric shaft having rollers operating within said chambers, oscillatory members engaging said rollers, and said body having intake pockets at its circumference leading to said chambers and outlet passages leading from said chambers terminating in a restricted outlet opening communicating with the casing interior.

5. A power transmitting device, comprising a casing adapted to contain a liquid, a chambered body rotatably mounted within 75 said casing, an eccentric shaft and a pair of rollers operating within said chambered body, a pair of oscillatory members engaging said rollers, a rocking device adapted to hold said oscillatory members in working engagement with said rollers, and said body having intake pockets leading to its chambered interior and provided with a restricted outlet communicating with the interior of 80 said casing.

85 In testimony whereof I affix my signature.

JOSEPH F. JAWROWSKI.
